[57] CLAIM

The ornamental design for a photographic camera, as shown and described.

DESCRIPTION

FIG. 1 is a right rear perspective view of a photographic camera showing our new design;

FIG. 2 is a left front perspective view thereof, with a combined lens cover and flash unit in a closed position;

FIG. 3 is a left front perspective view thereof, with the combined lens cover and flash unit in an erected position.

The ornamental face plate pattern is understood to continue uniformly through the area of said face plate.

FIG. 1

FIG. 2

FIG. 3
